US00D726827S

(12) **United States Design Patent**
Togano

(10) **Patent No.:** **US D726,827 S**
(45) **Date of Patent:** **** Apr. 14, 2015**

(54) **DOCUMENT VALIDATOR WITH STACKER**

(71) Applicant: **Japan Cash Machine Co., Ltd.**, Osaka (JP)

(72) Inventor: **Keiichi Togano**, Tokyo (JP)

(73) Assignee: **Japan Cash Machine Co., Ltd.**, Osaka (JP)

(**) Term: **14 Years**

(21) Appl. No.: **29/449,135**

(22) Filed: **Mar. 14, 2013**

(30) **Foreign Application Priority Data**

Oct. 1, 2012 (JP) 2012-23951

(51) **LOC (10) Cl.** **20-01**

(52) **U.S. Cl.**

USPC **D20/8**
